UNITED STATES PATENT OFFICE.

WILLIAM N. WALKER, OF ROME, NEW YORK.

INTERNAL-COMBUSTION ENGINE.

1,130,045.

Specification of Letters Patent. Patented Mar. 2, 1915.

Application filed May 8, 1913. Serial No. 766,396.

To all whom it may concern:

Be it known that I, WILLIAM N. WALKER, of Rome, in the county of Oneida, in the State of New York, have invented new and useful Improvements in Internal-Combustion Engines, of which the following, taken in connection with the accompanying drawings, is a full, clear, and exact description.

This invention relates to certain improvements in internal combustion engines of the four-cycle type and refers more particularly to the construction of the rotary valves and associated ports for controlling the inlet of the explosive mixtures and exhaust products of combustion.

The main object is to control the inlet and exhaust through a single port in the cylinder by means of a rotary valve synchronized with the movement of the piston and provided with peripheral inlet and exhaust ports alternately registering with the port in the cylinder at the proper time.

Another object is to control such ports of a multiplicity of cylinders through the medium of a single valve having peripheral inlet and exhaust ports registering with their respective cylinder ports in synchronism with the movement of the corresponding pistons. In other words, I have sought to obviate the noise and unreliability incidental to the use of puppet valves and at the same time to increase the efficiency of the engine by making a single port for each cylinder serve for the inlet of the explosive mixture and exhaust for the spent gases.

Another object is to provide simple means for balancing the rotary valve under the varying pressures to which it is subjected.

Other objects and uses will be brought out in the following description.

In the drawings—Figure 1 is a longitudinal vertical sectional view of a six-cylinder internal combustion engine embodying the various features of my invention. Fig. 2 is a horizontal sectional view through the same engine in the plane of the rotary valve. Fig. 3 is a transverse vertical sectional view through the first cylinder at one end of the engine. Figs. 4 and 5 are face views of the detached valves for each set of three cylinders. Fig. 6 is a horizontal sectional view of a three-cylinder internal combustion engine showing a slightly modified form of rotary valve. Fig. 7 is a longitudinal vertical sectional view through the valve case and also portions of

the cylinders shown in Fig. 6. Fig. 8 is a transverse sectional view through the left hand end cylinder and valve case shown in Figs. 6 and 7. Fig. 9 is a face view of the detached valve shown in Figs. 6, 7 and 8. Fig. 10 is an enlarged transverse sectional view through the center of one of the valve drums and adjacent portion of the cylinder showing the position of the valve when the piston is at the limit of its inward movement ready to take in a fresh charge of the explosive mixture, the recess in the cylinder to assist in balancing the pressure on the valve being omitted, the section being taken through the center of one of the valve drums.

The engine shown in Figs. 1 to 4 inclusive comprise a series of, in this instance six, cylinders —1— which are preferably cast in sets of three cylinders each and securely fastened in an upright position side by side to an underlying supporting frame or bed —2— having a crank case —3— common to all of the cylinders and in which is journaled a crank shaft —4—, the latter being connected in the usual manner by pitmen —5— to their respective pistons —6—.

Each cylinder is provided in one side near its upper end or head with a port —7— which serves both as an inlet for the explosive mixture and an exhaust for the spent gases or products of combustion, these ports being located at the same side of all of the cylinders and communicate directly with 90 longitudinally extending cylindrical valve casings —8— running along the same side of the cylinder in close proximity thereto and arranged end to end in axial alinement with their adjacent ends open and communicating with an inlet passage —9— common to both valves as shown more clearly in Figs. 1 and 2. This inlet passage —9— may be connected by a conduit —10— to a carburetor or other mixing device through 100 which the explosive mixture is passed from the source of supply (not shown) to the cylinders.

Rotatably mounted in the valve casings —8— are tubular cylindrical valves —11—, 105 arranged coaxially end to end, one for each set of cylinders and driven at the same rate of speed, preferably, by separate power transmitting devices so as to move in synchronism with the movement of the pistons, 110 each of said power transmitting mechanisms, preferably, consisting of angle gears

—12— secured respectively to the crank shaft —4— and an upright shaft —13— and additional angle gears —14— secured respectively to the upper end of the upright shaft —13— and adjacent end of the corresponding tubular valve —11—.

Each of the valves —11— is provided with a series of, in this instance three, cylindrical drums —15—, —15'— and —15''—, one for each cylinder, and intervening annular exhaust channels —16— registering with corresponding exhaust ports —17— which communicate with an exhaust chamber —18— having a relatively large outlet —19— adapted to be connected to any suitable manifold (not shown) or open to the atmosphere as may be desired.

The outer ends of the valves —11— carrying the corresponding angle gears —14— are closed but their inner adjacent ends are open and communicate with the fuel inlet —9— so that the explosive mixture which may be drawn into the inlet by the suction stroke of any one of the pistons in a manner hereinafter described will also pass into the valves.

The gears —12— and —14— are proportioned to rotate the valves —11— at one-fourth the speed of that of the crank shaft —4— so that the valve makes one-eighth revolution for each stroke of the piston. These valves are rotated in the direction indicated by arrow —X— and each valve drum is provided with separate sets of inlet ports —20—, balancing ports —21— and exhaust ports —22—, like ports being arranged diametrically opposite each other so that the inlet port, balancing port and exhaust port of each set follow each other in sequence in the direction of rotation of the valve. The inlet port and exhaust port of each set are of substantially the same circumferential length corresponding to the length of the port —7— and are spaced apart a distance corresponding to their lengths, leaving an intervening peripheral portion —23— of substantially the same length as the port —7— for closing the same when the inlet and exhaust ports are positioned at opposite sides thereof.

Each inlet port —20— extends radially through the wall of the valve drum and communicates with the interior chamber as —24— thereof so that as soon as the exhaust port —23— is cut off from communication with the port —7—, the inlet port —20— will just begin to open communication with said port —7— and will maintain such communication while the piston is traveling from the limit of its inward movement to the end of its extreme outward or suction stroke, thereby drawing the explosive mixture from the inlet passage —9— through the interior of the valve and thence through the ports —20— and —7— into the com-

bustion chamber of the cylinder. These inlet ports —20— and also the balancing ports —21— terminate short of the ends of their respective valve drums so as to cut off communication with the annular channels but are of substantially the same width as the corresponding cylinder ports —7— with which they are adapted to register as the valve is rotated, the balancing ports —21— extending only part way through their respective valve drums from the periphery thereof so as to form pockets in said peripheries which pockets are connected by diametrically extending tubes —25— as shown more clearly in Fig. 10 for the purpose of equalizing the pressure at opposite sides of the valve especially during the compression and firing strokes of the piston. The exhaust ports —22— are also formed in the peripheries of their respective valve drums and extend part way or through the valve thereof, thereby forming axially extending ports in said peripheries communicating with the annular exhaust channels —16— so that when any one of these exhaust ports is registered with the corresponding cylinder port or ports —7— during the inward exhaust stroke of the piston, it will allow the spent gases to be expelled from the cylinder through that port and thence through the annular passage —16— to the exhaust chamber —18— and thence to the muffler or to the atmosphere as may be desired. The ports —22— in the end drums of each valve terminate short of the ends of the valve to cut off communication with the inlet —9— at one end and prevent escape of the gases at the opposite end.

It is now clear that the opposite halves of the periphery of each valve drum is provided with an inlet port, a balancing port and an exhaust port, arranged in sequence in the direction of rotation of the valve and are successively registered with the cylinder ports —7— in a manner hereinafter described, the balancing ports —21— being somewhat longer circumferentially than the inlet port or exhaust port and preferably extend approximately equidistant from the adjacent ends of the tube —25— so as to establish communication between the interior of the tube and cylinder port —7— during the greater part of the compression and firing strokes when the pressure upon the side of the valve nearest the cylinder is greatest, thereby equalizing the pressure at the opposite side of the valve through the tube. In order that this balancing of the valve may be more effective, the valve case may be provided with recesses —26— Fig. 3 diametrically opposite the cylinder port —7— and of substantially the same axial length as the balancing ports which are adapted to register therewith as the valve rotates.

In Figs. 6 to 9 inclusive, I have shown a three-cylinder engine as provided with a slightly modified form of valve in which the inlet ports, as —20—, extend inwardly 5 from the peripheries of the valve drums part way through the wall thereof, thereby forming peripheral pockets extending axially through one end only of the corresponding drums to communicate with annular recesses or channels —9— in the periphery of the valve while the exhaust pockets —22— communicate with similar annular recesses or channels —16—. In this modification, as shown more clearly in Figs. 10 10 and 7, the annular recesses or channels —9— alternate with the exhaust channels —16— and are in constant communication with the inlet ports —10— while the exhaust channels —16— are in constant communication with the exhaust ports —17—. The ports —10— and —17— are preferably located in one side of the valve case 15 opposite the cylinder ports —7—, the like ports being connected by suitable manifolds (not shown).

When the inlet pockets and exhaust pockets are constructed in the manner shown in Figs. 6 to 9 inclusive, the opening through the center of the tubular valve may be used 20 for the circulation of a cooling fluid, such as air or water, while the valve casing and cylinder may be provided with a water jacket —27—, as shown, each cylinder being also provided with a spark plug —28— located in the upper end thereof, preferably 25 opposite the ports —7—.

Operation: In the operation of the construction of valve shown in Figs. 1 to 5 inclusive and Fig. 10, assuming that the valve is rotated in the direction indicated by arrow —X—, Fig. 10, and that the piston is at the limit of its inward stroke ready to begin its outward or suction stroke, during which time the cylinder port —7— will be closed 40 by the part —23— of the valve, while the exhaust port —22— will have just passed the cylinder port —7— and the inlet port —20— of the valve will be at the opposite side of said cylinder port ready to open communication therewith, then during the outward or suction stroke of the piston, the valve will have been rotated an eighth of a revolution causing the inlet port —20— to register therewith and move across and to 45 the opposite side of the cylinder port —7—, thus allowing the explosive mixture to be drawn through the chamber —24— and into the combustion chamber of the cylinder. Now, as the piston moves inwardly through 50 its compression stroke, the valve will be rotated another one-eighth of a turn, thereby moving the succeeding balancing port —21— into registration with and across the cylinder port —7—, allowing a part of the mixture under compression to be forced through 55

the tube —25— to the opposite side of the valve for balancing the pressure upon said valve, the tube being relatively small so as not to perceptibly reduce the compression of the mixture in the combustion chamber. 70 Now, as the piston reaches the limit of its inward compression stroke, the compressed gases are ignited by the spark plug —28—, thereby driving the piston outwardly through its firing stroke and causing the rotation of 75 the valve through the third one-eighth turn during which the active balancing port will still maintain communication with the cylinder port to allow a part of the exploded gases to pass through the tube —25— to the 80 opposite side of the valve for equalizing the excess pressure due to the expanded gases. Then, as the piston returns through its fourth or exhaust stroke, the valve will be caused to rotate another one-eighth turn to 85 register the succeeding exhaust port —22— with the cylinder port —7— and allow the gases in the cylinder to be expelled by the inwardly moving piston through the exhaust port —22— and into the communicating 90 channel or channels —16— and thence outwardly through the exhaust channel —18—. The piston is now in its starting position at the limit of its inward stroke while the valve, which has just been turned a half 95 revolution, will be in a position to repeat the operations just described through the remaining half of its revolution as the piston moves through its suction stroke, the compression stroke, firing stroke, and exhaust stroke.

The operation of the valve shown in Figs. 6 to 9 inclusive is substantially the same as that described for the valves shown in Figs. 1 to 5 inclusive and Fig. 10 and it is, therefore, believed to be unnecessary to further describe this operation for the modified structure.

What I claim is:

1. In an internal combustion engine, a cylinder having a single port serving both for the fuel-inlet and exhaust, a rotary valve having in its periphery an inlet port, a balancing port and an exhaust port, said ports being arranged in sequence in the direction of rotation and successively registering with the cylinder port. 110

2. In a four-cycle internal combustion engine, a cylinder having a port serving for the fuel inlet and exhaust of the spent gases, a rotary valve having in its periphery separate sets of ports arranged in sequence and movable successively into registration with the cylinder port, each set comprising an inlet port, a balancing port and an exhaust port, and means for rotating the valve one-eighth of a revolution for each stroke of the piston. 120

3. In a four-cycle internal combustion engine, a cylinder having a single port serv- 130

ing as an inlet for the fuel and as an exhaust for the spent gases, a rotary valve having in its periphery an inlet port, a balancing port and an exhaust port arranged in sequence, 5 said balancing port being in one side of the valve and having communication with the opposite side of the valve, and means for actuating said valve at such speed that its inlet port will be moved across the cylinder 10 port while the piston is moving through its suction stroke and the exhaust port moved across the cylinder port during the exhaust stroke of the piston, said balancing port being of sufficient length to register with 15 the cylinder port while the piston is moving through its compression stroke and firing stroke.

4. A rotary valve, comprising a tubular shell having peripheral annular grooves and 20 recesses connecting with the grooves for the inlet, and peripheral annular grooves and recesses connecting with the grooves for the exhaust, a recess opposite each port in the valve chamber exposing an amount of valve

surface equivalent to the area of the port, 25 and ports leading directly through the valve and suitably disposed in angular relation to one another serving to permit the cylinder pressure to be equalized on both sides of the valve whenever the inlet and exhaust ports 30 are closed, thus balancing that member and relieving it of the frictional load due to side pressure.

5. A rotary valve, comprising a tubular shell having peripheral annular grooves and 35 recesses connecting with the grooves for the inlet, and peripheral annular grooves and recesses connecting with the grooves for the exhaust, and balancing ports through the valve for equalizing the pressure from the 40 compression and explosion strokes.

In witness whereof I have hereunto set my hand this 30 day of April, 1913.

WILLIAM N. WALKER.
